US00D605093S

(12) **United States Design Patent**
Lohr et al.

(10) **Patent No.:** **US D605,093 S**
(45) **Date of Patent:** **** Dec. 1, 2009**

(54) **BICYCLE PARKING RACK**

(75) Inventors: **Joshua G. Lohr**, Madison, WI (US);
Jeffery T. Iverson, Madison, WI (US);
Jereme D. Noffke, Madison, WI (US)

(73) Assignee: **Saris Cycling Group, Inc.**

(**) Term: **14 Years**

(21) Appl. No.: **29/332,013**

(22) Filed: **Feb. 6, 2009**

(51) **LOC (9) Cl.** **12-11**

(52) **U.S. Cl.** **D12/115**

(58) **Field of Classification Search** **D12/115, D12/120; 211/5, 17-22, 182; 70/233-235; 248/176.1, 551, 309.1, 552, 553, 127; 280/293; D6/449, 462**

See application file for complete search history.

(57) **CLAIM**

The ornamental design for a bicycle parking rack, as shown and described.

DESCRIPTION

FIG. 1 is an isometric view of a bicycle parking rack incorporating our new design, wherein the portions illustrated in phantom illustrate environment and form no part of the claimed design;

FIG. 2 is a right side elevation view thereof, the left side elevation view being a mirror image;

FIG. 3 is a front elevation view thereof;

FIG. 4 is a rear elevation view thereof;

FIG. 5 is a top plan view thereof; and,

FIG. 6 is a bottom plan view thereof.
